Primary Examiner — Mehri F Bajoul**CLAIM**

The ornamental design for a handheld game console, as shown and described.

DESCRIPTION

FIG. 1 is a bottom, front and right side perspective view of a handheld game console showing my new design;
FIG. 2 is a top, front and right side perspective view thereof;
FIG. 3 is a bottom, rear and left side perspective view thereof;

FIG. 4 is a front elevational view thereof;
FIG. 5 is a rear elevational view thereof;
FIG. 6 is a right side view thereof;
FIG. 7 is a left side view thereof;
FIG. 8 is a top plan view thereof; and,
FIG. 9 is a bottom plan view thereof.

The broken lines in the drawings illustrate portions of the handheld game console which form no part of the claimed design.

The oblique shade lines in the drawings represent reflective surfaces.
